W. J. GLADUE,

LOOM SHUTTLE.

APPLICATION FILED SEPT. 25, 1920.

1,361,714.

Patented Dec. 7, 1920.

UNITED STATES PATENT OFFICE.

WILFRED J. GLADUE, OF WOONSOCKET, RHODE ISLAND, ASSIGNOR TO SHAMBOW SHUTTLE COMPANY, OF WOONSOCKET, RHODE ISLAND, A COPARTNERSHIP COMPOSED OF CHRISTOPHER J. SHAMBOW AND JEANNETTE SHAMBOW.

LOOM-SHUTTLE.

1,361,714.

Specification of Letters Patent.

Patented Dec. 7, 1920.

Application filed September 25, 1920. Serial No. 412,722.

To all whom it may concern:

Be it known that I, WILFRED J. GLADUE, a citizen of the United States, residing at Woonsocket, in the county of Providence and State of Rhode Island, have invented 5 new and useful Improvements in Loom-Shuttles, of which the following is a specification.

This invention relates to means for clamping a bobbin on the pivoted spindle of a 10 loom shuttle, when the spindle and bobbin are operatively located in the chambered body of the shuttle, and for automatically releasing the bobbin when the spindle is displaced, or swung outward from the body.

Heretofore the bobbin has been clamped by a single clamping member arranged to engage the inner side of the bobbin.

My invention has for its object to more 20 firmly clamp the bobbin than heretofore, and is embodied in a shuttle having an inner clamp adapted to engage the inner side of the bobbin, and an outer clamp adapted to engage the outer side of the bobbin, so that 25 the latter is clamped at two diametrically opposite points, the arrangement being such that when the spindle is in its operative position, both clamps are engaged with the bobbin, and when the spindle is displaced, 30 both clamps are disengaged from the bobbin.

Of the accompanying drawings forming a part of this specification,—

Figure 1 is a top plan view of a shuttle embodying the invention.

Fig. 2 is a bottom plan view of the same.

Fig. 3 is a fragmentary view, showing a portion of the shuttle body in section, a portion of the spindle in elevation, and a portion of the bobbin by dotted lines, the 40 clamps being engaged with the bobbin.

Fig. 4 is a view similar to a portion of Fig. 3, showing the spindle partially displaced, one of the clamps being disengaged from, and the other engaged with the bobbin.

Fig. 5 is a view similar to Fig. 3, showing the spindle completely displaced, and both clamps disengaged from the bobbin.

Fig. 6 is a section on line 6—6 of Fig. 1.

50 The same reference characters indicate the same parts in all of the figures.

In the drawings, 12 represents a loom shuttle body, which may be of any suitable form and construction, and is chambered to

contain the spindle 13 and a bobbin 14 on the 55 spindle.

The spindle is provided with a base 15, mounted to swing on a transverse pivot pin 16, fixed to the body and passing through the chamber thereof.

In carrying out my invention I provide the shuttle with a pair of clamps, an inner clamp 19, and an outer clamp 20, adapted to simultaneously engage notches 17 and 18, formed in opposite sides of the bobbin base, 65 one of said clamps 19 being carried by the shuttle body, and the clamp 20 by the spindle base, and clamp-controlling means, including elements carried by the body, and elements carried by the spindle base, said 70 means having provisions for simultaneously engaging the clamps with a bobbin when the spindle is in its operative position, and being operable by the displacement of the spindle to disengage the clamps from the 75 bobbin.

The construction of the clamps and the organization of the said controlling means are preferably as next described.

The inner clamp 19 is composed of a 80 spring arm, bearing at one end on the seat 21 formed in the shuttle body, and engaged between its ends by a headed screw 22, fixed to the body. The free end of the clamp 19 has an ear 19^a, constituting the acting portion of the clamp, and adapted to spring 85 into engagement with a notch 17 in the bobbin.

The body 12 is provided with a fixed stop 23, which is a pin passing through the chamber of the body, and arranged as shown by Fig. 3, to limit the movement of the inner stop toward the spindle 13.

The construction thus far described does not differ materially from that employed in 95 single clamp shuttles in common use, the clamp 19 being adapted to enter a notch in the bobbin when the spindle and bobbin are in their operative position shown by Fig. 3, the stop 23 confining the clamp 19 against 100 movement in one direction, so that when the spindle and bobbin are swung outward, the bobbin notch leaves the stop ear 19^a, and the latter is disengaged from the bobbin.

The spindle base 15 is provided with an 105 ear 24, which displaces the stop 19 when the spindle is displaced, as indicated by Figs. 4 and 5.

The stop member 23, which has heretofore had only the function above stated, has, in accordance with my invention, another function, said stop constituting an element of controlling means whereby the outer clamp 20 is disengaged from the bobbin when the spindle is fully displaced, as shown by Fig. 2.

The outer clamp 20 is an arm movably mounted on the spindle base 15, and provided at one end with an ear 20^a, adapted to enter a bobbin notch 18, and constituting the acting portion of the clamp. The opposite end of the clamp is preferably bent to a 10 guide member 25, in sliding contact with a guiding face on the spindle base. A stud 26 is fixed to the outer clamp at a point between its ends, and is slidable in a socket in the spindle base. A spring 27 15 interposed between the head 26^a of the stud 26 and a shoulder in the spindle base, normally holds the outer clamp in its bobbin-engaging position, as shown by Fig. 3.

The arrangement is such that when the 25 spindle is in its operative position, the ear of the outer clamp 20 is held by the spring 27 in position to engage a bobbin notch.

When the spindle is displaced by being 30 swung outward, the outer clamp remains in engagement with the bobbin until the spindle has moved from the position shown by Fig. 3, to that shown by Fig. 4, so that the outer clamp remains in engagement with the bobbin after the inner clamp is disengaged therefrom. When the spindle is moved 35 farther outward from the position shown by Fig. 4, the stud head 26^a abuts against the stop 23, and is moved by the latter against the force of the spring 27, until the outer 40 clamp is disengaged from the bobbin, as shown by Fig. 5. The clamps 19 and 20 are therefore successively disengaged from the bobbin, the inner clamp being displaced during the movement of the spindle from 45 the position shown by Fig. 3, to that shown by Fig. 4.

It will now be seen that I have provided 50 clamp-controlling means carried in part by the body 12, and in part by the spindle base, for simultaneously engaging the clamps with the bobbin when the spindle is moved to its operative position, and for disengaging the clamps from the bobbin when the spindle is displaced, the inner clamp being 55 preferably disengaged before the outer clamp. Said means may be otherwise embodied without departing from the spirit of the invention.

It will be seen by reference to Fig. 6 that 60 the acting edges 19^a and 20^a of the clamps 19 and 20 are parallel with each other and each extends crosswise of the shuttle body and substantially parallel with the inner or bottom face of the latter. This arrangement causes the grooves 17 and 18 in the

bobbin base to extend crosswise of the shuttle body when the bobbin is secured. Said grooves are parallel with the sides of the usual feeler slot 30 in the bobbin base so that the clamps hold the slot 30 in position 70 to register with the feeler slot 31 in one side of the shuttle body. A shuttle previously equipped with only a clamp 19 may be provided with the additional clamp 20 by providing the body with a spindle carrying the 75 clamp 20, or by connecting the clamp 20 as shown with an ordinary spindle. The two clamps hold the bobbin so firmly that there is no possibility of even a slight rotative movement of the bobbin in the spindle, such 80 as might occur if but one clamp were employed. Liability of wearing or chipping the base of the bobbin at the ends of the clamp-receiving groove therein, is thus prevented.

85 I claim:

1. A loom shuttle comprising a chambered body, a bobbin spindle having a base pivoted to the body, a pair of clamps formed and arranged for simultaneous engagement 90 with opposite sides of a bobbin on the spindle, one of said clamps being carried by the body, and the other by the spindle base, and clamp-controlling means carried by the body and by the spindle base, said 95 means having provisions for simultaneously engaging the clamps with a bobbin when the spindle is in its operative position, and being operable by the displacement of the spindle to disengage the clamps from the 100 bobbin.

2. A loom shuttle substantially as specified by claim 1, said means being organized to disengage the clamps successively.

3. A loom shuttle comprising a chambered body, a bobbin spindle having a base pivoted thereto, an inner bobbin clamp, means yieldingly connecting the inner clamp to the body, said clamp being adapted to yieldingly engage the inner side of a bobbin when the spindle is in its operative position, an outer bobbin clamp formed and arranged to engage the outer side of the bobbin, and means yieldingly connecting the outer clamp with the spindle base, and normally holding the outer clamp in its bobbin-engaging position, means operable by the displacement of the spindle being provided for displacing each clamp from its bobbin-engaging position, when the spindle is displaced.

4. A loom shuttle comprising a chambered body, a bobbin spindle having a base pivoted in the body, an inner bobbin clamp composed of a spring arm secured at one end portion to the body, and having an ear at its free end adapted to engage a notch in the inner side of a bobbin on the spindle when the latter is in its operative position, an outer bobbin clamp composed of an arm 130

movably mounted on the spindle base, and having an ear adapted to engage a notch in the outer side of the bobbin, a stud fixed to the outer clamp and slidable in the spindle 5 base, a spring carried by the spindle base and acting on said rod to normally hold the outer clamp in its bobbin-engaging position, and a fixed stop in the body, arranged to co- operate with said spring arm and spring-
10 pressed stud in disengaging the ears of the

inner and outer clamps from the bobbin when the spindle is displaced.

5. A loom shuttle substantially as specified by claim 5, said stop being arranged to disengage the outer clamp after the disen- 15 gagement of the inner clamp.

In testimony whereof I have affixed my signature.

WILFRED J. GLADUE.
